UNITED STATES PATENT OFFICE

FRANK McLAUGHLIN, OF TORONTO, ONTARIO, CANADA, ASSIGNOR TO MARION FREDENBERG, OF TORONTO, CANADA

DISPENSING CONTAINER

Application filed December 7, 1927. Serial No. 238,408.

This invention relates to dispensing containers for brushes; that is, devices including a reservoir for material such as soap, mucilage, ink, paint, or the like, the material being forced through the discharge outlet by means of a piston within the container, which piston is actuated by means of a threaded stem.

While arrangements for the same purpose are known, these earlier arrangements are comparatively expensive to manufacture, and further, as the actuating part is usually outside the container, there is always more or less danger of its being rendered inoperative due to damage through a fall or knock on account of the light materials usually employed in devices of this kind.

My object, therefore, is to devise an arrangement in which the operating mechanism is protected against damage in case of a fall or knock, and which at the same time is cheap and simple in construction.

I attain my object by means of the constructions hereinafter described and illustrated in the accompanying drawings in which

Fig. 1 is an enlarged sectional view of the device;

Fig. 2 a view illustrating the method of assembly;

Fig. 3 a plan view of the lower end of the container;

Fig. 4 a side elevation showing the container ready for shipment;

Fig. 5 a sectional view illustrating a modified arrangement; and

Fig. 6 a plan view of the flanged and rotatable disk as shown in Fig. 5.

In the drawings like numerals of reference indicate corresponding parts in the different figures.

1 is the container, which is of tubular form and preferably of thin aluminum. The container is open at its lower end and is provided with a discharge outlet in its upper end.

Within the lower end of the casing is sleeved a flanged disk 2, the flange being provided with an outwardly extending edge 3, adapted to engage the end of the casing to

limit the inward movement of the flanged disk. Positioned within the flanged disk is a rotatable disk 4, which disk is adapted to rotate a threaded stem 5 extending into the interior of the casing through a hole in the flanged disk 2.

Threaded on the stem within the casing is a piston 6, which piston frictionally engages the inner wall of the casing and is thus held from rotation.

To retain the rotatable disk in place, an annular member 7 is sleeved within the flanged disk. This annular member is formed with an inwardly directed flange 8, and also an outwardly directed flange 9, by means of which it is adapted to be double seamed to the lower end of the casing, thus securing the flanged disk 2 in place.

The rotatable disk is provided with tongues or projections 10 adapted to be engaged by the fingers when it is desired to rotate the disk.

It will thus be seen that the rotatable disk and threaded stem will be held from movement longitudinally of the container no matter which way the disk is rotated.

The piston may be of any desired construction. I show it as formed with a central portion 6^a of cork, rubber or similar material and at each side thereof a metal plate 6^b is secured thereon. A convenient way of securing the metal plates to the central portion is by means of prongs 6^c stamped up from the plates.

The interior of the casing is shouldered adjacent its discharge end to limit the movement of the piston. The discharge end is provided with a threaded outlet, and the outer end thereof is flanged inwardly and then outwardly to form an annular groove 11. A resilient dispensing tube 12, having a slit 13 cut in its outer end, is provided with a flat circular flanged portion 14 having a downwardly directed flange about its periphery, which flange has formed thereon an inwardly directed bead 15 adapted to be received in the groove 11.

I show my device used in conjunction with a shaving brush, the brush head being provided with a central aperture through which

extends the dispensing tube 12. The dispensing tube is preferably straight sided for a part of its length, the lower portion being somewhat tapered.

5 The brush head comprises a threaded cap 15 adapted to be threaded on the threaded outlet of the casing and having a tubular extension 16 forming a guide and protection for the dispensing tube 12. About the 10 cap is positioned a band 17, the recess between the band 17 and the tubular extension 16 forming the space for the butts of the bristles 18. The under side of the brush head preferably engages the top of the flange 15 of the dispensing tube and clamps it against the grooved end of the casing, thus preventing accidental disengagement due to pressure of the contents.

The bristles are preferably provided with 20 a metal binding band 19, the engaging surfaces of the said band 19 and the interior of the band 17 being suitably knurled to prevent rotation of the bristles relative to the head.

25 As it is desirable that the user be able to see the amount of soap which is exuded from the dispensing tube, I preferably give the end of the latter a slight outward curve as indicated in Fig. 1.

30 In Fig. 4 the dispensing container is shown ready for shipment, a cap 20 being screwed on the end of the container. A suitable cork or other seal will be placed in the cap to make the discharge end of the container air tight. To protect the material at 35 the lower end of the container, I preferably place over the bottom of the container a rubber cap 21.

In the construction described, the piston 40 may be easily retracted to permit of refilling of the container. If it is desired to prevent refilling, I may, as shown in Fig. 5, stamp up from the flanged disk 2 spring fingers 21 which are adapted to engage in notches 45 formed in the rotatable disk and prevent movement in the reverse direction.

In this form the container 1 is also slightly flared with the larger diameter at the bottom. In this case the part 6^a of the plunger 50 will be formed of a material adapted to be compressed and to retain said compressed shape when pressure is released. As the plunger is forced to the top of the container the diameter of the plunger is thus reduced, 55 with the result that if an attempt is made to lower the plunger, it disengages from the wall of the container and therefore rotates with the stem and does not move any farther downwardly. A double protection against 60 refilling is thus afforded.

The tapered container also forms a more convenient handle, as the danger of slipping from the hand is reduced.

What I claim is:

65 1. A dispensing container having an open

end; a flanged disk sleeved within said open end and forming a closure therefor; a rotatable disk at the outer side of said flanged disk; a threaded stem rotatable with said rotatable disk, said flanged disk having an 70 opening through which the stem extends; a piston threaded on said stem within the casing; and an inturned flange on said container adapted to retain the rotatable disk in its position against the flanged disk. 75

2. A dispensing container having an open end; a flanged disk sleeved within said open end and forming a closure therefor; a rotatable disk at the outer side of said flanged disk; a threaded stem rotatable with said 80 rotatable disk, said flanged disk having an opening through which the stem extends; a piston threaded on said stem within the casing; and an annular member adapted to be sleeved within the flanged disk, having an 85 inturned flange adapted to retain the rotatable disk in its position against the flanged disk and an outturned flange seamed to the lower end of the container.

3. A dispensing container having an open 90 end; a flanged disk sleeved within said open end and forming a closure therefor, the flange of said disk having an outwardly directed portion adapted to engage the end of the container; a rotatable disk at the 95 outer side of said flanged disk; a threaded stem rotatable with said rotatable disk, said flanged disk having an opening through which the stem extends; a piston threaded on said stem within the container; and an 100 annular member adapted to be sleeved within the flanged disk and having an inturned flange adapted to retain the rotatable disk in its position against the flanged disk and an outturned flange adapted to overlie the 105 outwardly directed portion of the flanged disk, said flanged disk and annular member being seamed to the lower end of the container.

4. A dispensing container having an open 110 bottom; a flanged disk sleeved within said open bottom; a rotatable disk in said flanged disk; a threaded stem rotatable with said rotatable disk, said flanged disk having an opening through which the stem extends; a piston threaded on said stem; an inturned flange on said container adapted to retain the rotatable disk in its position adjacent the flanged disk; and means for preventing 115 movement of the rotatable disk in one direction, comprising spring fingers on said flanged disk, said rotatable disk being provided with shoulders adapted to be engaged by the spring fingers. 120

5. A dispensing container comprising a 125 tubular casing having an open end; a threaded rotatable stem; a piston threaded on said stem; a rotatable disk within the casing and accessible through said open end for operating said stem said disk being provided 130

with finger-engaging means; and means forming part of the container for preventing movement of said disk longitudinally of the casing in either direction.

5 6. A dispensing container comprising a tubular casing having an open end; a threaded stem; a piston threaded on said stem; a rotatable disk within the casing and accessible through said open end for operating said stem; and means for preventing movement of said disk longitudinally of the casing in either direction, said container being tapered with its smallest diameter at its upper end, the piston being normally of 10 a size to fit the portion of largest diameter, and having a peripheral portion formed of compressible material.

7. A dispensing container having an open end and an inturned flange at said open end; 20 a threaded stem rotatable in said container; a rotatable disk, for actuating said stem positioned within the container and abutting said flange, said disk being provided with finger-engaging means; a piston threaded on 25 said stem; and means within the container and forming part thereof adapted to retain the disk in its position against the flange.

Signed at Toronto, Canada, this 30th day of November, 1927.
